Patented Aug. 6, 1912.

UNITED STATES PATENT OFFICE.

THOMAS N. SMITH, OF PORTSMOUTH, VIRGINIA.

SAND-DRIER.

1,034,656.

Specification of Letters Patent.

Patented Aug. 6, 1912.

Application filed July 7, 1911. Serial No. 637,246.

To all whom it may concern:

Be it known that I, THOMAS N. SMITH, a citizen of the United States, residing at Portsmouth, in the county of Norfolk and 5 State of Virginia, have invented a certain new and useful Sand-Drier, of which the following is a specification.

This invention relates to driers and more particularly to apparatus for drying sand.

10 The principal object is to provide a comparatively simple, inexpensive, and efficient apparatus of the character stated.

Other objects, as well as the nature, characteristic features and scope of the invention 15 will be apparent from the following description taken in connection with the accompanying drawing, forming a part hereof, which is a sectional elevational view of a sand drier embodying my invention.

20 In apparatus of this character prior to my invention much of the heat generated was dissipated or wasted through the stack and radiation was relied on to effect the drying. In the present apparatus this objectionable feature is obviated and the drying is effected by direct draft as well as by radiation in consequence of which there is little or no wastage of heat.

25 Referring to the drawing, *a*, represents a suitable heater; *b*, represents a superstructure involving a sand-holder and a heat deflector; *c*, represents a stack; and *d*, represents a cover. The heater or furnace *a*, is equipped with a suitable grate 1, an ash pit 2, and with fuel and ash doors 3, and 4. Mounted upon the furnace is a flanged ring or annulus 5, that supports the superstructure, including the sand container, heat deflector and stack. The sand receptacle em- 30 bodies a hopper 6, that is held to place by the flanged ring 5, and a cone-like wire fabric 7, which constitutes a screen for the sand and of such a mesh as to permit the sand to pass freely. The ring or annulus 5, is perforated as at 8, to permit the falling sand to pass into a chute 9, and a valve 10, is provided to close said perforations when desired, for example, when the fire is started in order to prevent a back draft.

40 The heat deflector 11, is interposed between the heater and stack and with its top or crown 12, tends to throw the heat outwardly against the hopper 6, and the sand screen. Said deflector is preferably a hollow cone-like casting, the part 11, constitut- 45

50 The heat deflector 11, is interposed between the heater and stack and with its top or crown 12, tends to throw the heat outwardly against the hopper 6, and the sand screen. Said deflector is preferably a hollow cone-like casting, the part 11, constitut-

ing a hopper and having a discharge chute 13, the major portion of which is in the hot air chamber of the heater. The part 11, is secured against displacement by suitable bridges 14, which are seated on the ring or 60 annulus 5. The top or crown 12, is superposed in spaced relation with respect to the element 11, by means of ribs or bridges 15, of different lengths that are notched so as to engage the ledge of deflector element 11. 65 By this construction and arrangement openings 16, are established through which some of the sand falls into the receptacle-like element 11, from whence it is conveyed by the chute 13, to a suitable point of recovery. 70 In other words, the element 11, is not only a heat distributor or deflector, but also an auxiliary sand discharge.

Certain of the ribs or bridges 15, are continued to near the top of the sand hopper 6, 75 and they constitute supports for the screen 7, and also act with their associates as distance-pieces for defining the hot air passage around the deflector to the stack. They also support the base section 17, of the stack. 80 This part 17, may be a casting and has a flange 18, that engages the supporting bridges and holds the screen in position.

The cover *d*, is cone-shape and is arranged to take into the sand hopper. It has a 85 sleeve 19, which slides on the stack and is sustained and adjusted by means of a cable 20, running over pulleys 21, and secured for example by a cleat 22. Access is had to the sand hopper for cleaning purposes through 90 the medium of a door 23. When the sand hopper is of especially large size, the standards 24, are provided as a further means of support.

In the practice of the invention, the valve 95 10, is moved to closed position when the fire is first started so as to avoid a back draft. As soon as the fire has gained sufficient headway, the valve is opened to permit the falling dry sand to pass into the chute 9. The 100 space between the heat deflector or element 11, and the screen and hopper is directly connected with the hot air chamber 25, and constitutes a dome-like hot air zone through which the sand must travel before reaching the chutes or outlets 9 and 13. Obviously, therefore, the sand is not only dried by radiation of heat from the shell and deflector but also by subjection to a hot blast. Consequently there is very little, if any, dissipa- 110

tion or wastage of heat energy. The cover *d*, when dropped to closed position tends to retain the heat and also to prevent the emission of sparks.

5 The hopper element 11, of the heat deflector may be independent of its chute 13, for facility in assembling the parts. This provision is clearly illustrated in the drawing in which the neck of the chute and the 10 throat of the hopper have interlocking complementary flanges 26 and 27, and the chute is secured at its top by ribs 28, secured in turn to bridges 14.

15 It will be obvious to those skilled in the art to which the invention relates that modifications may be made in details without departing from the spirit and scope of the invention. Hence the same is not limited other than required by the state of the prior 20 art.

Having described the nature and objects of the invention, I claim:—

1. A sand drier embodying a heater, a sand-holder equipped with a screen and 25 with a cover, a heat distributor intermediate said heater and holder, a valved main sand discharge outlet, and an auxiliary sand discharge outlet for the heat distributor.

2. A sand drier embodying a heater and 30 its complementary stack, a sand-holder equipped with a screen, a heat deflector or distributor above the heater and co-operating with the sand-holder to form a dome-like hot air passage from the heater to the stack 35 through which sand falls from the screen, and suitable means for discharging the dry sand.

3. A sand drier embodying a heater and 40 its complementary stack, a perforated ring or annulus carried by said heater, a sand hopper seated on said ring and having a screen feed, a cone above the heater and co-operating with the hopper and screen to establish a hot air zone through which the sand falls, 45 a valve operatively arranged with relation to

the annulus, and an adjustable cover for the hopper.

4. A sand drier embodying a heater and its complementary stack, a cone intermediate the heater and stack, a hopper surrounding 50 the cone and forming therewith a passage to the stack, and means for discharging the sand in a shower through said passage.

5. A sand drier embodying a heater and its complementary stack, a perforated hollow 55 cone intermediate the heater and stack and having a sand discharge, a hopper surrounding the cone and having a cone-like screen for discharging sand upon and around the hollow cone, a perforated annulus seated 60 upon and projecting beyond the heater and constituting the bottom of the hopper, a valve for the same, and a sand chute operatively disposed with relation to said annulus. 65

6. The combination of a heater and its stack, a heat deflector intermediate the same, a sand-holder and screen surrounding said deflector and forming therewith a passage to the stack, and a cover slidably mounted 70 on the stack in operative relation with the sand-holder.

7. A sand drier embodying a heater, a sand holder in detachable relation therewith and equipped with a screen and with an adjustable cover, a heat distributor intermediate said heater and holder, a valved main sand discharge chute in operative relation with the holder, and an auxiliary sand discharge chute for the heat distributor, said 80 chutes traversing the heater, substantially as described. 75

In testimony whereof I have hereunto signed my name in the presence of two subscribing witnesses.

THOS. N. SMITH.
